UNITED STATES PATENT OFFICE

CHARLES SAMUEL FRANKLIN, OF LONDON, ENGLAND, ASSIGNOR TO RADIO CORPORATION OF AMERICA, A CORPORATION OF DELAWARE

THERMIONIC TUBE

Application filed October 26, 1929, Serial No. 402,689, and in Great Britain November 2, 1928.

This invention relates to thermionic three-electrode tubes or valves, and has for its principal object to provide an improved triode capable of being satisfactorily employed for the 5 generation of very high frequencies.

Thermionic three-electrode valves, as at present in common use, comprise a cathode, usually consisting of a heated filament, a control electrode, usually consisting of a grid or 10 mesh of wire or wires, and an anode, generally in the form of a plate. It is found that limitations to the frequencies of the oscillations which may be obtained with valves of this kind are imposed by the leads connecting 15 the control grid system to the external circuit, by the current carrying capacities of these leads and of the grid wires themselves, and by the inability sufficiently to cool the grid electrode or conduct away the heat produced 20 therein.

According to this invention the control electrode of a thermionic valve is made in the form of a metal plate, cylinder, cone, or other solid construction, as distinct from a 25 wire construction.

In carrying out the invention, the active portions of the control electrode, i. e., those portions which mainly influence the electron flow, are formed as ribs or other projections 30 upon a solid electrode situated on the side of the cathode remote from the anode, the said ribs or the like projecting into the cathode-anode space to any extent necessary to give a desired degree of control. The projections, 35 which may or may not be integral with the main body of the control electrode, should be in good electrical and thermal contact therewith.

The invention is illustrated in the accompanying schematic drawing, in which Figure 40 1 is a sectional elevation and Figure 2 a sectional plan of a so-called transverse construction of valve in accordance with the invention. Figure 3 is a section showing the 45 construction of the control electrode incorporated in the valve shown in Figures 1 and 2.

Referring first to Figures 1 and 2, a valve 50 comprises a disc-shaped metal anode A opposite which is concentrically mounted a solid disc-shaped metal control electrode G,

which is provided with slots or grooves S in which are arranged filament portions F as shown. The electrodes A and G are separated and supported by glass parts M to which the appropriate electrodes are fixed by 55 suitable vacuum seals. The filament portions may be in series, parallel or series-parallel, as may be desired, the connections K therefor being brought through the glass, 60 as shown in Figure 1.

As will be seen, the electrodes are in so-called transverse arrangement, both control electrode and anode being in the form of disc-like members. The control electrode G is formed with slots or grooves S in which 65 are arranged the filament portions F, as clearly shown in cross-sectional Fig. 3.

It will be seen that the present invention provides a valve in which both the anode and the control electrode may be of ample current 70 carrying capacity, while both these electrodes may be arranged to be cooled by oil or similar mediums. Further, the difficulties hitherto experienced in making adequate connections to the control electrode are minimized or obviated. 75

What I claim is:

1. A thermionic tube comprising a disc-shaped anode, a disc-shaped grid electrode adjacent and parallel to said anode, the grid 80 electrode being provided with grooves, an electron emitting electrode positioned within the said grooves and a cylindrical member open at each end, interposed between and having its ends joined to said anode 85 and grid electrodes.

2. A thermionic tube comprising a disc-shaped anode forming one portion of the tube envelope, a disc-shaped grid electrode positioned opposite to said disc-shaped 90 anode and forming another portion of the tube envelope, an electron-emitting element mounted between said grid and anode electrodes, and means interposed between said disc-shaped grid and anode electrodes maintaining said electrodes in spaced relation. 95

3. A thermionic tube comprising a disc-shaped anode forming one portion of the tube envelope, a disc-shaped grid electrode positioned opposite to said disc-shaped anode 100

and forming another portion of the tube envelope, a cathode mounted between said grid and anode electrodes, and a glass portion interposed between said disc-shaped grid and anode electrodes maintaining said electrodes in spaced relation, both said electrodes and the glass portion being the sole means comprising the tube envelope.

CHARLES SAMUEL FRANKLIN.
